T. O. SCHRADER

COOLER DOOR CONTROL LOCK

Filed June 17, 1924

Fig. 1.

Fig. 7.

UNITED STATES PATENT OFFICE.

THOMAS O. SCHRADER, OF ALLENTOWN, PENNSYLVANIA, ASSIGNOR TO THE DENT HARDWARE COMPANY, OF FULLERTON, PENNSYLVANIA, A CORPORATION OF PENNSYLVANIA.

COOLER-DOOR CONTROL LOCK.

Application filed June 17, 1924. Serial No. 720,483.

To all whom it may concern:

Be it known that I, THOMAS O. SCHRADER, a citizen of the United States, residing at Allentown, in the county of Lehigh and 5 State of Pennsylvania, have invented certain new and useful Improvements in Cooler-Door Control Locks, of which the following is a specification.

My invention has relation to locks for 10 cooler doors employed in restaurants, meat shops, hotels, and other similar establishments; and particularly of a character in which the lock is operable from both the inside and outside of the cooler or refrigerator, that is, of a type in which it makes no 15 difference whether the lock holding the cooler door closed is in engagement with a keeper, after the person has entered the refrigerator for any purpose, as release can be had instantly from the inside of the cooler or refrigerator by means of a lever rod or bar so arranged as to throw the lock 20 out of engagement with its keeper holding the door in a fixed closed position.

25 In the foregoing connection my invention comprises a metal lock arranged and operable either left or right-handed and consisting of the structural arrangement of such a lock for the defined purposes hereinafter 30 fully described and claimed.

The nature and characteristic features of 35 my present invention will be more fully understood from the following description taken in connection with the accompanying drawings forming part hereof, in which—

Figure 1 is a perspective view of a cooler or refrigerator with a controllable lock in application thereto, embodying the main features of my present invention.

40 Figure 2 is an enlarged front elevational view, showing the control locking device in a normally operative position in connection with the door of a cooler or refrigerator and in a closed position of said door, with 45 said cooler or refrigerator looking in the direction of the arrow—*y*.

Fig. 3 is a vertical sectional view of the control lock in direction of the arrow 3—3 of Fig. 2, showing the internal arrangement of 50 the said lock, with the same in a condition when the door of the refrigerator is closed against the box or cooler; and also showing the position of the lever-rod from the rear of the door, for releasing the lock from its

normal position from the inner side of the 55 cooler box or refrigerator.

Fig. 4 is a rear elevational view of a section of the cooler door and a plan view of the inner operating lever-rod or bar of the said cooler control lock in the direction 60 of the arrow—*x* of Fig. 3.

Fig. 5 is a horizontal sectional view through the control lock, showing the preferred arrangement of the crank-like roller bearing bolt for engaging and disengaging 65 to and from the keeper and thereby either holding closed or permitting of instant release of the door from the cooler box or refrigerator either from the inside or outside, and taken on the line 5—5 of Fig. 2. 70

Fig. 6 is a vertical sectional view of the control lock, showing the operating lever-rod in a position with the crank-like lock bolt released from the keeper therefor; and also showing the position of the inner lever- 75 rod or bar adjustably connected by means of a link with the operating means controlling the bolt lock and coil spring connected therewith for freeing the same from the inside of the cooler or refrigerator; and 80

Fig. 7 is a modified arrangement of the cooler lock, showing a horizontal section therethrough, and in this instance showing the crank-like lock bolt on the right-hand side of the housing concealing the operating means for said bolt and levers, for the manipulation of the same from either the outside or inside of the cooler or refrigerator. 85

Referring to the drawings, *a*, is the refrigerator or cooler box fitted with a controllable locking device of the present invention and of one of the types in arrangement for door closing and occupying a left-handed position, as illustrated in Figs. 1 to 6, inclusive, of said drawings. This device *b*, comprising a box-like housing *b*¹, slotted in part at *b*², and through which projects a lever operating rod *b*³, having a bearing collar *b*⁴, fitting around a cross 100 crank-like shaft *b*⁵, flat in one part as at *b*⁶, and as clearly shown in Figs. 5 and 7. This collar is held rigid to said shaft by means of a set screw *b*⁷, so as to permit of turning of the said shaft and thereby of the operation 105 of the crank-like extremity *b*⁸, arranged to engage in a keeper *c*. This keeper is incliningly arranged to permit of the roller *b*⁹, carried

on the end of the bolt b^8 , to engage in the substantially U-shaped portion of the said keeper c , and so as to prevent disengagement of the same until released by operating the said lever-rod b^3 . The bearing collar b^4 , of the said lever-rod b^3 , is provided with a lug c^4 , for the pivot c^5 , of a link c^6 , adjustably pivoted to a lug c^7 , extending from the inner portion of the housing b^1 , and held in operative position eccentrically with respect to the position of the lever-rod b^3 , thereof. Mounted on the link c^6 , is a tensile coiled spring e , the respective extremities of which bear against the said lugs and when the lever-rod b^3 , is operated to bring the said spring into a more or less compressed concentric condition with respect to the said lever-rod and in which is held in a closed position of the door, by means of the crank-like bolt engaging the keeper c . The roller b^9 , carried on the lock bolt b^8 , may be readily removed by loosening the set screw b^{10} , arranged in the outer end of the said bolt b^8 , as clearly illustrated in Fig. 2.

The control lock is preferably made of malleable iron and the bolt of hardened cast steel or other material. The said bolt in an operative position is under control of the coiled spring and the lever-rod b^3 , serves only to provide the means for shifting the said bolt as required, against the normal tension of the said spring, in its eccentric relationship, and under in a release position, the lessening of the compressing effect of the said spring, when assuming substantially opposite eccentric relationship, in respect to the then shifted position of the lever-rod from a depending inclining position, such as is illustrated in Figs. 2 and 3, to a substantially horizontal position, such as illustrated in Fig. 6. Connected with the bar c^6 , is a link c^9 , extending rearwardly through an opening c^{10} , of the door a^1 , as in Figs. 3 and 6. This link is provided in its rear extremity with a series of perforations c^{11} , for engaging a bell crank lever-rod c^{12} , pivoted to a bracket c^{13} , secured removably to the inner side of the door, as clearly shown in Figs. 3 and 6, and so as to permit as so positioned of the moving of the spring e , into a compressible condition as in Fig. 6, and thereby of the shifting of the lever-rod b^3 , into a substantially horizontal position, and also to cause the control lock bolt to become free of the keeper c , holding it in a position to open the door of the cooler box or refrigerator.

In Figs. 1 to 6, inclusive, the crank-like lock bolt extends from the left-hand extremity of the housing concealing the operating means of the lock, as clearly shown in Fig. 2, while in Fig. 7, the crank-like bolt, carrying the roller b^9 , is arranged right-handed with respect to the housing concealing the oper-

ating means for the same, as hereinbefore described.

The foregoing arrangement of a control lock operable from either side of the movable member to which applied renders the same safe against accidents such as becoming locked in a cooler or refrigerator. This is highly desirable as well as very important against loss of life. Again the taking apart of the lock as well as assembly of the same is a very simple operation for making repairs or replacing a broken part of the same.

Furthermore, the desired leverage required for lockingly holding in fixed relationship, the movable member through a keeper applied to the rigid member, is efficiently accomplished according to the device arranged as hereinbefore described, and under an exceedingly economical means readily assembled and easily adjusted in respect to parts for use.

Having thus described the nature and objects of my invention, what I claim as new and desire to secure by Letters Patent is:

1. A control locking device, comprising a keeper, a locking bolt for engaging said keeper having an extension, a housing in which said extension is journaled, a lever operating rod having a collar normally fitted within said housing to said extension, and the collar of said lever operating rod having a lug, a link pivoted to said lug and adjustably connected to the lug of said housing, for holding said link in one position substantially eccentric with respect to that of said lever operating rod, a coil spring in bearing contact at respective extremities with said lugs, to permit said lever operating rod in actuation to thereby cause said spring to assume a substantially opposite position with respect to the normal position of said link and said lock bolt freed of engagement with said keeper, substantially as and for the purposes described.

2. A control locking device, comprising a keeper, a locking bolt for engaging said keeper having an extension, a housing in which said extension is journaled, a lever operating rod having a collar normally fitted within said housing to said extension and the collar of said lever operating rod having a lug, a link pivoted to said lug and adjustably connected to the lug of said housing, for holding said link in one position substantially eccentric with respect to that of said lever operating rod, a coil spring in bearing contact at respective extremities with said lugs, to permit said lever operating rod in actuation to thereby cause said spring to assume a substantially opposite position with respect to the normal position of said link and said lock bolt freed of engagement with said keeper, a link connected with said extension and projecting rearwardly through the opening and closing fix-

ture and means adjustably pivoted to said link and to a bell crank lever, for operating said locking bolt from an opposite position, substantially as and for the purposes described.

3. A control locking device, comprising a keeper, a locking bolt for engaging said keeper having an extension, a housing in which said extension is journaled, and said bolt at the extremity carrying a removable roller, a lever operating rod removably fitted to said extension, a link pivotally connected to said extension and adjustably connected with a fixed member housing said extension for supporting said link normally in a substantially eccentric position with respect to the position of said lever operating rod, a

spring surrounding said link and bearing against said extension and housing member for permitting said lever operating rod in 20 actuation to thereby cause said spring to assume a substantially opposite position in respect to the normal position of said link and with said lock bolt freed of engagement with said keeper, substantially as and for the 25 purposes described.

In witness whereof, I have hereunto set my signature in the presence of the two subscribing witnesses hereto.

THOS. O. SCHRADER.

Witnesses:

MABEL G. DAVIS,
ELIZABETH M. PRICE.
